[57] **CLAIM**

The ornamental design for a combined fuel pump and canopy structure for a service station, as shown and described.

DESCRIPTION

FIG. 1 is a perspective view of a combined fuel pump and canopy structure for a service station showing my new design;

FIG. 2 is a side elevational view thereof, the opposite side being a mirror image of that shown;

FIG. 3 is a front elevational view thereof, the rear being a mirror image of that shown;

FIG. 4 is a top plan view thereof;

FIG. 5 is a bottom plan view thereof;

FIG. 6 is an enlarged perspective view of the first of two types of pump components thereof;

FIG. 7 is an enlarged front elevational view of the first of two types of pump components thereof, the rear being a mirror image of that shown;

FIG. 8 is an enlarged side elevational view of the first of two types of pump components thereof, the opposite side being a mirror image of that shown;

FIG. 9 is an enlarged horizontal cross-sectional view of the first of two types of pump components thereof, taken along line 9—9 of FIG. 7;

FIG. 10 is an enlarged rear elevational view of the second of two types of pump components thereof, the front and sides being identical to those shown in FIGS. 7 and 8; and

FIG. 11 is an enlarged horizontal cross-sectional view of the second of two types of pump components thereof, taken along line 11—11 of FIG. 10. The canopy and other pump components have been omitted from FIGS. 6-11 for clarity of illustration.
